RESISTOR ELEMENT.

Application filed April 22, 1925. Serial No. 24,983.

This invention relates to new and useful improvements in resistor elements, and more particularly to elements of small size appropriate for use in radio apparatus.

One of the objects of this invention is to provide a resistor whose initial resistance may be accurately predetermined and adjusted, and which, when so constructed, has a stability and permanence of resistance which is independent and irrespective of atmospheric conditions such as barometric pressure, and is free from disturbance by accidental shock. Heretofore, resistor elements have been constructed for use in radio apparatus, but these elements have largely been subject to the difficulty that their resistance could not be accurately predetermined, and when calibrated were subject to variations from day to day by reason of changing atmospheric conditions, and from moment to moment by reason of local conditions of the apparatus in which they were employed, and if dropped upon the floor, or tapped accidentally with a tool, would oftentimes permanently change their resistance. This resulted in poor operation of the set in which they were employed, since for use with vacuum tubes, it is essential that the resistance should not change within major limits, but must remain very close to the calibrated amount stated upon the label.

A further object is the provision of a resistor element in which the resistance may be accurately adjusted at the factory, and the resistor element held in this adjusted condition throughout its life.

With these and other objects in view, we have represented on the accompanying drawings several forms of construction of this resistor element, but all embodying the same generic principle of stability and accuracy. In these drawings—

Figure 1 is a longitudinal section of a resistor element according to this invention;

Figures 2 and 3 are longitudinal sections of modified forms of construction; and

Figure 4 is section on an enlarged scale showing the relative dimensions of the plunger piston and the granules.

Referring particularly to Figure 1, we have shown a tube 1 of insulating material having the proper structural strength, such as lavite. We have found this material very suitable for our purpose, since it is substantially free from any absorption or of permeation by the moisture of the atmosphere;

and has also sufficient strength to receive screw threads and be subjected to a considerable strain both in compression and tension. At the ends of this tube 1 are formed screw threads to receive interiorly screw threaded caps 2, 2'. The end wall 3 of each of these caps has an aperture to receive the threaded spindle 4 which has on its end, a plunger 5. The central bore through the sleeve 1 is indicated at 6, and is made as near as possible circular and concentric with the outer periphery of the sleeve and with the caps 2, 2', so that the plunger 5 is carried substantially centrally within this bore hole 6. A lock nut 7 is provided for holding this screw threaded spindle 4 in adjusted position. An outer cap 8 is screwed or forced onto the closing cap 2 to provide smooth outer and end surfaces for making contact.

Within the bore hole 6 is placed a mixture of conductive and non-conductive materials. After experimentation, we have found that the most suitable mixture for this purpose is comprised of finely divided lampblack and talc. These substances are mixed together in proper proportions as may be determined by experiment, to afford substantially the desired resistance for the cross-section and the length available between the plunger heads 5, 5 of the element. We prefer to have these materials so finely comminuted that they pass a two hundred mesh screen. It is obvious that as the proportion of talc relative to lampblack is increased, the resistance of a given length of material of the same cross-section will be increased.

The plunger 5 is not constructed for a tight fit within the borehole 6, but is made to fit somewhat loosely therein. The annular space thus afforded between the sleeve 1 and the plunger 5 should be of the order of a thousandth of an inch or less, that is, less than the approximate diameters of the particles. We have found that a clearance of a .001 inch is excellent, since it prevents the small particles from passing the plunger 5, but does not prevent the free escape of air.

In constructing and assembling one of these elements, one cap and plunger assembly is placed in position, and the mixture of lampblack and talc is placed in the borehole 6. The element is jarred and tamped during the process to obtain a fairly homogeneous and equally compressed mass. The

other end cap and plunger are then placed in position, and the two plungers are screwed down on to the mass with considerable pressure. As the mass is thus compressed and compacted, its resistance drops until the galvanometer or ohmeter reading indicates that the calibrated and desired resistance has been attained. The lock nuts 7 are then turned down and secured to hold the 10 plungers in their adjusted position. It is desirable to use a spot of solder to hold the lock nut and spindle in adjusted position. The outer end of the spindle 4 is then clipped off, and the covering caps 8 placed in position.

We have found that if the plunger 5 fits tightly within the bore hole 6, the air contained within the mixture of lampblack and talc is not permitted to escape, but apparently tends to segregate in small bubbles which seriously affect the resistance of the mass as a whole. In the course of time, these bubbles may escape. The pressure upon and in the mass then changes, and the resistance 25 no longer remains constant; thus preventing any easy calibration, and affecting the permanency of the resistances constructed. With our construction, however, the escaping air passes through the annular space 30 around the plunger head into the chamber about the spindle 4, where it has full opportunity to expand without affecting the resistance. Obviously the escape of air may occur through the structure of the plunger, 35 when perforated or permeable.

On the other hand, the element is completely shut off from the outer atmosphere, and is not subject to barometric variations. Since the powdery mixture is wholly 40 enclosed and held under firm pressure against any shifting of position, blows or even dropping will not change its resistance when once adjusted.

It is obvious that by varying the composition of the mixture, resistances of any value from one hundred ohms to five or ten meg-ohms may be provided within one and the same outer shell.

Although the above represents one form 50 of the resistance, which may be called a

"cartridge" form, since it resembles the ordinary cartridge fuse, and may be employed in a similar manner, it is obvious that other forms may be made by utilizing conical caps 8, or forms such as those shown in Figures 55 2 and 3. In Figure 2, the closing cap 12 carries the spindle 4 and lock nut 7 as before, but the spindle 4 is allowed to project a considerable distance to receive a clamping nut 13 for securing the end of a connecting 60 wire 14. In Figure 3, the construction is the same as in Figure 2, but the element may be employed in a cartridge fuse socket.

Having thus described our invention, what we claim is:

1. In a resistor, a resistance composition comprising a mixture of finely divided lampblack and talc.
2. In a resistor, a resistance composition comprising a mixture of finely divided lampblack and talc in a compacted form.
3. In a resistor, a resistance composition comprising a mixture of finely divided and compacted lampblack and talc substantially free from air bubbles under pressure.
4. In a resistor element, an insulating tube having screw threads on its exterior at each end, closing caps mounted on said screw-threaded ends, screw-threaded spindles fitted through said caps, plungers on said spindles within said tube and affording free escape to the air between said plungers and tube while holding the resistance composition in compacted condition, locking nuts to hold said spindles in defined positions and caps enclosing said spindles and locking nuts.
5. In a resistor element, an insulating tube having screw threads on its exterior at each end, closing caps mounted on said screw-threaded ends, screw-threaded spindles fitted through said caps, plungers on said spindles within said tube and affording free escape to the air between said plungers and tube while holding the resistance composition in compacted condition.

In testimony whereof, we affix our signatures.

CLARENCE S. STEWARD.
CHARLES F. BROWN.
